UNITED STATES PATENT OFFICE.

GEORGE D. BURTON, OF BOSTON, MASSACHUSETTS, AND GEORGE W. STEINER, OF NEW YORK, N. Y.

ELECTRICALLY-OPERATED RAILWAY-GATE.

SPECIFICATION forming part of Letters Patent No. 656,091, dated August 14, 1900.

Application filed April 22, 1899. Serial No. 714,151. (No model.)

To all whom it may concern:

Be it known that we, GEORGE D. BURTON, of Boston, in the county of Suffolk and State of Massachusetts, and GEORGE W. STEINER, of the city of New York, (Brooklyn,) in the county of Kings and State of New York, have invented a new and useful Improvement in Electrically-Operated Railway-Gates, of which the following, taken in connection with the accompanying drawings, is a specification.

Our invention relates to an electrical apparatus and operating mechanism adapted to open and close railway-gates; and it consists in the construction and arrangement of the several parts whereby the person in charge can readily control several gates by the manipulation of a single lever or switch.

Our invention is illustrated in the accompanying drawings, in which—

Figure 1 is a view in elevation, showing two gates as applied to an ordinary grade-crossing. Two sidewalk-gates are also shown in connection with the street-gates. Fig. 2 shows in elevation and section the electrical and mechanical apparatus used for raising and lowering the gates. Fig. 3 is a plan showing the same parts that are shown in Fig. 2. Fig. 4 shows, partly in plan and partly diagrammatically, the switch and wire system used.

In the drawings the street-gates are indicated by A A, and the sidewalk-gates by B B. The street-gates are hung on shafts A', and the sidewalk-gates on shafts B'. The shafts A' and B' are rigidly connected to their respective gates and are provided with segment-gears A² B², which mesh into each other in such a manner as to cause both the street-gate and the sidewalk-gate to move together—that is, both go up or both come down at the same time. To the shaft A' a rocking lever C D is attached. To one end C of this rocking lever a solenoid-core C⁴ is connected by a link C² and pivots C' C³. To the other end D of the rocking lever a solenoid-piston D⁴ is connected by a link D² and pivots D' D³. (See Fig. 2.) M and M' represent the solenoids. Counterweights W W are attached to the street-gates A A.

The shafts A' and B' are supported by the frame E, and the operating mechanism is pro-

tected by a casing E'. The switch device and system of wiring are shown in Fig. 4, which will now be explained. The switch-box S is provided with resistance-coils of any suitable kind, the contact-buttons of which are designated by R. A lever L is pivoted at L⁵ and has upon it a contact-spring P⁴, connected to the generator G by conductors P³ P² P' P and the positive brush, (+). When the lever L is moved to the right, the contact-spring P⁴ connects with the resistance-coils through the buttons R and thence to the solenoids M M' M² M³, as will be explained. Instead of a dynamo G a storage battery may be used, if desired. A switch-blade N⁶ is pivoted to the lever L at L⁴. This switch-blade N⁶ is held in the position indicated in the drawings by a spring S'. Upon the lever L are two contact-clamps N⁵ and n⁵, insulated from each other and from the lever L, but electrically connected by means of N⁶ N⁷ N⁸ N⁹ N¹⁰ and brush (—) to the generator G. N⁴ and n⁴ are segment-arcs insulated but in contact with the contact-clamps N⁵ and n⁵, respectively. When the switch-blade N⁶ is in the position shown in Fig. 4, it is in electric connection with the contact-clamps N⁵; but when it is swung over, as indicated by dotted lines, then it is out of contact with the contact-clamp N⁵ and in contact with the contact-clamp n⁵.

The electrical circuits are as follows: To raise the gates, the attendant takes hold of that part of the handle designated by L'. Also grasping the handle L' of the switch-blade N⁶ he throws the switch-blade into its dotted position—that is, so that it is in electrical contact with the contact-clamp n⁵. Now by moving the lower lever to the right he makes contact with the buttons R, thus closing the circuit which energizes the solenoids M M², thus causing their pistons to be drawn in, (see Fig. 2,) which action is transmitted through the rocking levers D C raising the gates. The circuit in this case is from the (+) brush of the generator through the wires P P' P² P³, contact-spring P⁴, resistance R, wires P⁵ P' P⁷ to solenoids M' M³, thence from said solenoids through wires n n' n² n³, contact-arc n⁴, clamp n⁵, switch-blade N⁶, (in its dotted position,) wires N⁷ N⁸ N⁹ N¹⁰ to brush

(—) of the generator. To lower the gates, the attendant grasps the handle at L, leaving the switch-blade in contact with the clamp N⁵. Now by turning the lever to the right he closes 5 the circuit through the resistance R and energizes the solenoids M M², thus drawing the piston C⁴ down and closing the gates. The circuit in this case is as follows: Starting from the (+) brush, thence through the wires 10 P P' P² P³, contact-spring P⁴, resistance R, wire P⁵ P⁶ P⁷ to solenoids M M², and back through wires N, N', N², and N³ to contact-arc N⁴, spring N⁵, switch-blade N⁶, and wires N⁷ N⁸ N⁹ N¹⁰ to (—) brush and generator. The 15 bell-circuit is independent of the main resistance R, which is varying, and therefore not adapted for a bell-circuit. The bell electric line starts from the part T of the spring-contact piece P⁴, passes through the conductor-arc T, 20 wire T², resistance R², bell T⁴, wire T⁵ N⁹ N¹⁰ to generator. As arranged the bell will begin to ring as soon as the lever L is started from either position and will continue to ring as long as the gates are moving either in going 25 up or in coming down.

The solenoids may be wound in any of the approved methods. The following has proved very effective: Use No. 20 doubly-insulated magnet-wire, wind twenty-three layers, each 30 layer having two hundred and ninety-three turns, making six thousand seven hundred and thirty-nine total number of turns. In this case the weight of wire used is nineteen pounds seven ounces admitting a sufficient 35 current to sustain two hundred pounds.

We claim—

1. In an electrically-controlled railway device, the combination of a swinging gate, solenoids having cores connected to said gate, 40 and a circuit switch-lever having a movable switch-blade adapted to direct the electric current from one solenoid to the other.
2. In an electrically-controlled railway de-

vice, the combination of a swinging gate, a source of electricity, an electrical device for 45 operating said gate, and a current-controlling switch-lever having a contact adapted to close the circuit through the resistance and said electrical device, a movable switch-blade disposed on said lever, contacts adapted to connect said blade with contact-segments, and conductors connecting said contact-segments with the device for operating the gate.

3. In an electrically-controlled railway device, the combination of an electrical circuit 55 having a resistance disposed therein, solenoids disposed in said circuit, a pivoted lever having a contact for closing the circuit through said resistance, a movable switch-blade disposed on said lever and adapted to 60 direct the current from one solenoid to the other, contacts disposed on said lever and insulated therefrom, and conductors connecting said contacts with the solenoids.

4. In an electrically-controlled railway device, the combination of an electrical circuit having a resistance disposed therein, solenoids disposed in said circuit, a pivoted lever having a contact-spring for closing the circuit through the resistance, a movable switch-blade pivoted to said lever and adapted to 70 direct the current from one solenoid to the other, contacts disposed on said lever and insulated therefrom, contact-segments connected with said contacts, and conductors 75 connecting said segments with the solenoids.

In testimony whereof we have signed our names to this specification, in the presence of two subscribing witnesses, on this 14th day of April, A. D. 1899.

GEO. D. BURTON.
GEO. W. STEINER.
